UNITED STATES PATENT OFFICE.

CLAS J. JACOBSSON, OF NEW YORK, N. Y.

FALSE BOTTOM FOR GARBAGE-RECEPTACLES.

1,341,507.

Specification of Letters Patent.

Patented May 25, 1920.

Application filed January 25, 1919. Serial No. 273,093.

To all whom it may concern:

Be it known that I, CLAS J. JACOBSSON, a citizen of the United States, and a resident of the city of New York, borough of Manhattan, in the county and State of New York, have invented a new and Improved False Bottom for Garbage-Receptacles, of which the following is a full, clear, and exact description.

- 10 The object of the invention is to provide a new and improved false bottom for garbage cans and similar receptacles used in households, hotels, restaurants and other establishments, and arranged to maintain the 15 garbage receptacle in a sanitary condition when emptying it of its contents, especially protecting the bottom of the receptacle against adherence of moisture, fats and like matter.
- 20 In order to accomplish the desired result, use is made of a false bottom of paper or similar cheap material fitting onto the bottom of the garbage receptacle and provided with an upwardly extending marginal flange 25 engaging the inner surface of the wall of the garbage receptacle.

A practical embodiment of the invention is represented in the accompanying drawings forming a part of this specification, in 30 which similar characters of reference indicate corresponding parts in all the views.

Figure 1 is a sectional side elevation of the usual garbage can provided with the false bottom, the section being on the line 35 1-1 of Fig. 2;

Fig. 2 is a sectional plan view of the same on the line 2-2 of Fig. 1;

Fig. 3 is a plan view of the false bottom prior to inserting it into the garbage receptacle;

Fig. 4 is a similar view of a modified form of the false bottom; and

Fig. 5 is a side elevation of the same.

The false bottom 10 is made of paper or a 45 similar cheap material and is adapted to rest on the bottom 11 of a garbage can or receptacle 12 of usual sheet metal construction. The false bottom 10 is provided with a marginal flange formed of integral tongues 13 50 adapted to engage the inner surface of the wall of the garbage can 12 to prevent any moisture or semi-fluid from passing between the false bottom 10 and the regular bottom 11 of the garbage can. The tongues 13 are 55 cut or stamped out of the paper of which the false bottom is made, the latter being prac-

tically of a diameter corresponding to that of the garbage can to allow of readily placing the false bottom in position in the garbage can prior to filling the same with the 60 refuse materials. When the can is dumped of its contents the false bottom likewise passes out of the can with the refuse material and a new one can be placed by the householder in position in the can prior to 65 receiving another batch of refuse material. It will be noticed that by the use of this false bottom any moisture, greases, fats or the like are not liable to adhere to the bottom 11 of the garbage receptacle and hence 70 the latter is practically kept at all times in a sanitary condition.

Of course, the disk forming the false bottom 10 is in either case of a larger diameter than the diameter of the receptacle or can 75 12 so that when the marginal edge of the disk is bent or turned upwardly, the bottom will fit properly within the can.

The tongues forming the marginal flange may be in the shape shown in Fig. 3, or in 80 the form shown in Figs. 4 and 5, it being understood that in the former case the adjacent edges of successive tongues 13 are spaced by cutting out V-shaped portions of the paper to allow the edges of the tongue 85 13 to abut when the false bottom is in position, as clearly shown in Figs. 1 and 2 of the drawings, while in the form shown in Fig. 4 the paper is simply provided with radial slits to allow the tongues 14 formed thereby 90 to overlap at their adjacent edges when pushing the false bottom into the garbage receptacle.

The false bottom may be provided with a handle 15, preferably made of a strip of 95 paper secured at its ends to the false bottom 10 and having a portion normally folded up to permit of extending the handle into segmental shape, as indicated in dotted lines when using the handle for placing the false 100 bottom in position in the garbage receptacle.

It is understood that the false bottom can be very cheaply manufactured and hence is of no great expense to the householder.

The marginal flange 13 may be extended 105 to any desired height to practically form a lining for the interior of the receptacle.

Having thus described my invention, I claim as new and desire to secure by Letters Patent:—

1. As an article of manufacture a false bottom for garbage receptacles made of pa-

per and having an upturned integral resili-
ent flange adapted to engage the inner sur-
face of the receptacle to frictionally hold
the bottom on the bottom of the receptacle,
5 said bottom being provided with a handle
and adapted to be dumped out of the recep-
tacle with the contents thereof.

2. As an article of manufacture, a false
bottom for insertion in a garbage receptacle
10 made of paper and having upturned inte-

gral tongues adapted to engage the inner
wall surface of the receptacle, and a han-
dle attached to the false bottom for placing
the latter in position in the garbage recep-
tacle, said handle consisting of a strip of 15
greater length than the diameter of the bot-
tom and having a portion normally folded
up to permit of it being extended into seg-
mental shape.

CLAS J. JACOBSSON.
